UNITED STATES PATENT OFFICE.

HARVEY H. HALL, OF ADAMS COUNTY, COLORADO.

ELECTRICALLY-OPERATED DISAPPEARING BED.

Application filed March 29, 1923. Serial No. 628,637.

To all whom it may concern:

Be it known that I, HARVEY H. HALL, a citizen of the United States, and a resident of the county of Adams and State 5 of Colorado, have invented a certain new and useful Electrically-Operated Disappearing Bed, of which the following is a specification.

This invention relates to improvements 10 in that type of folding beds generally styled wardrobe beds or wall beds, the functioning and advantages of which are well understood for permanent installment in hotel rooms, apartments or otherwise, and from 15 a broader aspect the invention has been especially devised as an electrically operated disappearing bed.

The invention broadly and specifically embodies various novelly combined features, 20 not only as to the construction of the bedstead itself, with its pivotal mountings and associated arrangement of cooperating elements, but also with more particular reference to the manner of its electrical operation 25 from closed to opened position and vice versa under automatically actuated control.

The primary objects of the invention have been to produce such an improved type of 30 disappearing bed that may be readily installed, which does not require manual manipulation, which is durable and positively efficient in operation, and the operating mechanism of which provides means for securely holding the bed and its parts anchored in their full opened and closed positions, the said operating mechanism being automatically shut off at the end of 35 each opening and closing movement of the bed, while at the same time the electrical circuits therefor are reset by the automatic control of a pair of auxiliary electric switches for the reverse movement of the bed upon the actuation of a main electric switch.

40 The foregoing and other objects and advantages, however, will be so clearly apparent, as incidental to the following disclosure, that no useful purpose would be served by further enlarging upon the same initially, 45 and with these prefacing remarks, therefore, reference will now be immediately had

to the accompanying drawings, illustrating a practical but not necessarily the only embodiment of the invention, in which drawings—

55 Figure 1 is a view in vertical section through a floor and a cabinet, or wall compartment, showing in solid lines and in side elevation the disposition of the associated elements of the combined arrangement when the bed is fully opened or distended, and also illustrating in dotted outlines certain of the same elements in the positions they assume during a portion of either the closing or opening operations; Figure 2 is also 60 a vertical sectional and elevational view, but showing the bed and its pivotally associated elements in their closed or folded positions relatively to each other and to 65 said cabinet or wall compartment; Figure 70 3 is a plan view of the bed and its operating connections, being a transverse sectional view through the cabinet, or wall compartment, taken along the plane of the line 3—3 of Figure 1; Figure 4 is a diagrammatic view of the electrical circuits coupling 75 up a reversible motor with a manually operated main switch, and with a source of electrical energy, through the medium of a pair of automatically actuated auxiliary 80 electric switches; and Figure 5 is a view analogous to Figure 4, but with the several switches oppositely thrown for reversing operations.

85 Before actually proceeding with the description of the drawings proper, it may be said at the outset that, while I have illustrated the invention as associated with a wall recess or compartment, in employing the term cabinet, throughout the specification or claims, I employ the same in the sense of including either a fixed wall cabinet, wardrobe, recess or compartment, for a disappearing wall bed, or a movable cabinet or wardrobe, for a portable wardrobe 90 disappearing bed, or their equivalents. It may also be emphasized at the outset that, while the drawings show the bed as being end-folding or longitudinally foldable, it is to be understood that it might be made inner-side-folding or transversely foldable, 95 without substantial alteration in principle.

and wholly within the scope of the actual invention, should such an arrangement be desired.

A cabinet compartment, having a full 5 open front, is formed by the rear wall 6, the side walls 7, the top wall 8 and the bottom wall 9, which latter may be the floor 10 of a room when said cabinet compartment is in fact a recess in the wall proper 10 of the room.

A vertically disposed shaft 11 is rotatably mounted within the cabinet adjacent to its rear wall 6 and preferably in the center of the cabinet with reference to its side walls. 15 The shaft 11 is provided with a suitably threaded section or portion 12 and is geared up with a reversible type of electric motor 13, the said motor being shown as mounted by the top 8 of the cabinet and the said gearing being illustrated by a worm wheel 14, carried by one end of the shaft 11 and meshing with a driving worm carried by a stub shaft 15 of the motor. It will be obvious, however, that the exact type of gearing between the motor and the shaft is unessential, and also that the motor and the gearing element 14 need not necessarily be disposed outside of the cabinet, as there is plenty of vacant space at the upper rear inside 20 of the cabinet for the mounting of these elements if desired.

The threaded portion 12 of the shaft 11 functions as the actuating means for a vertically operated head block, which will be 35 hereinafter referred to more particularly, the said head block being provided with a bore therethrough that is internally threaded to encompassingly receive the threaded portion 12 of the shaft 11, and the said head block being operated upwardly or downwardly, or in reverse directions, dependent upon the direction of rotation of the shaft 11.

A manually operated main electric 45 switch is generally designated by its handle 16, being mounted at any convenient position relatively to the cabinet, and a pair of automatically actuated auxiliary electric switches are mounted in proximity 50 to and substantially in line with the threaded portion 12 of said shaft 11, which latter may be conveniently referred to as the actuating shaft.

This main switch 16 may be of any suitable type, but it is shown as being of three-pole double-throw construction, embodying the arms or blades 64-65-66 which are pivotally mounted, respectively as at 67-68-69, and cooperate with complementary 60 oppositely paired contact terminals 28-30, 70-71 and 72-73.

The said auxiliary switches are disposed in substantially spaced relation, one being located towards the upper end of the threaded portion 12 and the other towards the

lower end thereof, and they may be conveniently referred to as the upper and lower auxiliary switches 17 and 18 respectively. These switches 17-18 are shown as mounted upon the rear wall 6 of the cabinet, although they may be otherwise located, but they are so constructed and coupled together by suitable connecting means that when one is open the other is closed. The said connecting means may be flexible or inflexible, or may be a single or paired means, but as shown they preferably comprise a pair of rods 19 connected at their upper and lower ends, respectively, to throw-arms 20-21 of the upper and lower auxiliary switches, the said arms 20-21 being projected beyond their switch casings in a direction towards said threaded portion 12 of the actuating shaft 11, whereby they are alternately engaged and thrown into open position by means of a projection on said head block, the connecting means 19 at the same time causing the closing of the complementary auxiliary switch not then so engaged, all of which will herein- 85 after more fully appear.

A pair of conduit wires 22-23 lead respectively from the main switch 16 to the upper and lower auxiliary switches 17-18, and a conduit wire 24 also leads from said main switch 16 to one pole of the source of electrical energy. A branch conduit wire 25-25^a connects the auxiliary switches 17-18, while a conduit wire 26 leads from said branch wire 25-25^a to the motor 13, shown as in circuit with the field thereof and the latter being also in circuit with a conduit wire 27-27^a leading therefrom to the other pole of the source of electrical energy, which, although illustrated as a battery would ordinarily be the service line for the electrical fixtures of the building. The pivotal switch arm or blade 64 of the main switch 16 is always in circuit with the wire 24, as is also the blade 66, by way of the branch 74, and the center blade 65 is likewise in circuit with the return wire 27^a, by way of the branch 75. The pivotal switch points or arms of the auxiliary switches 17-18 are always in circuit with the branch wire 25-25^a the main and auxiliary, the switch contact terminals for the wire 22 being indicated at 28 and 29, and the main and auxiliary switch contact terminals for the conduit wire 23 being indicated at 30 and 31. Line wires 76-77 and 78-79 are respectively in circuit with the opposite ends of the motor armature coils and with their complementary contact terminals 72 and 70, while branches 80 and 81 respectively connect the contact terminals 73 and 71, across the main switch, with their complementary conduit 78 and 77. The pair of alternately completed electric circuits herein involved will be more defi- 115 120 125 130

nitely traced out with reference to the description of the opening and closing operations of the bed.

The side rails of the bed frame are indicated at 32 and the inner end rail at 33. The outer end of the bed frame is provided with pivotally suspended forward legs 34 and a rigid footboard element 35, while the inner end is provided with a rigid base section 36 of the head board and an upper head board section 37 that is pivotally connected as at 38 to said rigid base section 36. The inner end of the bed frame may also be provided with a transverse plate or bar 39, bolted to the end rail 33, which transverse bar 39 has a vertically disposed web or flange section 40 that lies up against said rigid base section 36 of the head board, or at least there is a web element that is equivalent to the flange portion 40 which is centrally located and is provided with rolled over edges of tubular form or analogous cylindrical bearings 41.

The inner end of the bed frame is not supported by upright legs, but a pair of side link bars 42 are pivotally connected at their upper ends to the side rails 32 at suitable positions 43 substantially forward of the rear end of the bed frame, while the lower ends of said link bars 42 are pivotally connected as at 44 to suitable base supports located just inside of the forward base portion of the cabinet. The rear or inner end of the bed frame may also be provided with laterally projected side rollers 45, which serve as end guide bearings operating in the vertical guideway slots 46 of a pair of track elements 47 that are complementally disposed at the forward inside lower portion of the cabinet.

48 designates a closure door or panel board, for the front opening of the cabinet, which is suitably hinged or pivotally supported at its lower end as at 49. Forwardly of its central portion, but rearwardly of the legs 34, the inside face of this door or panel board 48 may be provided with a triangular frame connection 52 that is which is apertured, as at 51, to freely receive the ends of suspending means between the bed frame and said panel board door. The said suspending means is illustrated as a triangular frame connection 52 that is open at its base, the leg ends of which pass freely through said apertures 51, being provided with terminal knobs 53 functioning as limiting stops, and the apex end of the triangular frame 52 being pivotally connected, as at 54, to the front or outer end rail of the bed frame. Obviously, however, this suspending means may be otherwise than as actually shown, and furthermore it may be stated that the legs or rods 52 are a little longer than the normal distance between the pivotal position 54 and the ap-

tures 51, when the bed is fully opened, thereby providing for a limited longitudinal play of the lower ends thereof through the apertures 51, which will be more clearly seen at Figure 1.

55 designates the vertically traveling head block, as heretofore referred to, which has a threaded vertical bore, indicated at 56, for operatively encompassing the threaded section 12 of the actuating shaft 11. This traveling head block may also be provided with a transverse forward bore 57 and a rearwardly located projection of lug 58, which latter is adapted to alternately engage and actuate the throw-arms 20-21, respectively, of the upper and the lower auxiliary switching elements, at the end of the upward and the downward movement of the traveling head block 55.

Connecting means are pivotally disposed between the said traveling head block and the rigid base portion 36 of the headboard of the bed frame, which connecting means are longitudinally rigid for functioning alternately as push-bar and a pull-bar unit. Such connecting means obviously may be otherwise than as actually shown, but it has been found convenient to form the same as a clevis-like or draw-bar-like coupling triangular link, the apex end of which is pivotally disposed within the transverse aperture 57 of the head block 55, while the base arm 60 of its legs 59 is pivotally mounted within said cylindrical bearings 41 of the web 40, although the base arm 60 need not necessarily be continuous, but may simply consist of inturned terminals of the legs 59, rotatably fitting within the tubular bearings 41.

In order to control the opening up and folding of the upper pivotal section 37 of the headboard of the bed frame, a pair of short side links or arms 61 are interposed between said upper pivotal section 37 and the legs 59 of the triangular coupling link, the said short arms 61 being pivotally connected to the former, as at 62, and to the latter as at 63.

Operation.

Assuming that all of the switches are set as shown at Figure 4, and that the bed is being operated from the closed up to the opened out position, then there is an appropriately closed main circuit, through the field of the motor 13, by way of the elements 24-67-64-28-22-29-17-25-26-27-27^a, and also an appropriately closed deviated circuit, providing for a divided out current, through the armature coils of the motor, by way of 24-74-69-66-72-76-77-78-79-70-65-68-75-27^a, all of which causes the motor to operate in the proper direction for actuating the head block 55 upwardly. When the bed has

reached the full opened position, with all of the parts located as shown in solid lines at Figure 1, then at the end of its upward travel the lug 58, of the head block 55, will have engaged the throw-arm 20 of the upper auxiliary switch 17 and thus opened the latter, while at the same time the connections 19 will have actuated the throw-arm 21 of the lower auxiliary switch 18 to close the same. The auxiliary switches 17 and 18 are now reset, as at Figure 5, for the bed closing up operations, but it is to be observed that the main switch 16 will not have been disturbed, and remains in the position shown at Figure 4, so that the circuits are broken and open, with the motor at rest. If now the main switch 16 is thrown to the opposite side, as at Figure 5, then a main closed circuit is again established, through the field of the motor, by way of 24—67—64—30—23—31—18—25—26—27—27^a, and also a deviated circuit is closed through the armature coils of the motor, but with its electric current flowing in a reversed or opposite direction to that heretofore described, by way of 24—74—69—66—73—80—78—77—81—71—65—68—75—27^a, all of which causes the motor to operate in a reversed direction, or opposite to that before described, for actuating the head block 55 downwardly. At the end of its downward travel, the lug 58 of the head block 55 will have engaged the throw-arm 21 of lower auxiliary switch 18, for resetting the auxiliary switches, as at Figure 4 and as will be understood, but without disturbing the main switch 16, so that again the circuits are broken and opened, for bringing the motor to a stop.

As the traveling block 55 is moved downwardly, under the rotatable wedge-feeding action of the screw section 12, the coupling link 59 functions as a push-bar means and exerts a continuous downward pressure on the inner end of the bed frame, whereupon the said inner end portion is gradually swung downwardly, as the rollers 45 are caused to descend in their side guideways 46, and thereby correspondingly swinging the outer end of the bed frame upwardly; the said bed frame being dually fulcrumed, as it were, by the vertically descending side end rollers 45 and its pivotal connections 43 with the swinging side link supporting arms 42, which said pivotal connections 43 travel in a proper arc, relatively to the descending rollers 45, to avoid any binding action of the parts.

As the outer end of the bed frame starts to rise, the panel closure or door 48 is not initially moved until the limiting stops or knobs 53, of the forward suspension means 52, have been moved into engagement with the vertical web 51 of the transverse angle bar 50, and thus a clearance space is pro-

vided for, between the panel door and the pivoting front legs 34 of the bed frame, to permit of the folding in of the said front legs as the bed frame is operated into closed up position within the cabinet.

The gradual movements of the various parts are fully obvious from the dotted outlines thereof, at Figure 1, and the completely folded up positions of all of said parts are likewise clearly apparent from Figure 2, without further detailed description.

If, now, it be desired to open up the bed, it is simply necessary to throw the main switch 16 to the position shown at Figure 4, whereupon the reversible motor 13 will be caused to rotate in a direction opposite to that previously described, with reference to the closing up of the bed. The traveling block 55 will then be caused to ascend, when the coupling link 59 will now function as a pull-bar means, the folding up operations previously described being now exactly reversed, as will be apparent.

From all of the foregoing it will be seen that no manual effort is required for raising or lowering the bed, nor are there any doors to be opened or closed manually. Furthermore, when the bed is in either its full open or full closed position, it is maintained positively secured or anchored in that position against any movement, even independently of its electrical control owing to the interposition of the bracing longitudinally rigid coupling link 59 between the inner end of the bed frame and the head block 55.

Although the invention has now been completely set forth, it is nevertheless to be understood that it is not necessarily limited to all of the details exactly as disclosed, excepting as they may come within the terms of the ensuing claims, or equivalent combinations of elements, or as fairly interpreted in the light of the specification if necessary.

What I do claim, as new and patentable, is:—

1. The combination with a cabinet, of a bed frame pivotally associated towards its inner portion with the base of said cabinet for foldable closing up therein and opening out therefrom, a vertically disposed threaded actuating shaft mounted rearwardly of said bed frame, a traveling element in threaded association with said shaft, means for operating said shaft in reverse directions of rotation, and longitudinally rigid pivotal connecting means between said traveling element and the inner portion of said bed frame.

2. The combination with a cabinet, of a bed frame pivotally associated towards its inner portion with the base of said cabinet for foldable closing up therein and opening out therefrom, the said bed frame having a rigid base head board section with a foldable upper head board section pivoted

thereto, a vertically disposed threaded actuating shaft mounted rearwardly of said bed frame, a traveling element in threaded association with said shaft, means for operating said shaft in reverse directions of rotation, longitudinally rigid pivotal connecting means between said traveling element and the inner portion of said bed frame, and pivotal connecting means between the aforesaid connecting means and said upper head board section.

3. The combination with a cabinet having upstanding guideways disposed therein at the lower sides thereof, of a bed frame providing projected elements at its inner portion movably fulcruming in retained association with said guideways, supporting arms pivotally connected at their upper ends to said bed frame at suitable positions substantially forward of said fulcruming elements and at their lower ends pivotally mounted in association with the lower ends of said guideways, supporting means for the outer portion of said bed frame, traveling means located rearwardly of said bed frame and mounted to be operated vertically in reverse directions, means for actuating said traveling means, and longitudinally rigid pivotal connecting means between

said traveling means and the inner portion 30 of said bed frame.

4. The combination with a cabinet, of a bed frame pivotally associated towards its inner portion with the base of said cabinet for foldable closing up therein and opening out therefrom, a vertically disposed threaded actuating shaft, a traveling element in threaded association with said shaft, longitudinally rigid pivotal connecting means between said traveling element and the inner portion of said bed frame, a reversible electric motor in circuit with an electrical source and in couple with said shaft, a main switch in circuit with said electrical source, an upper and a lower auxiliary switch mounted adjacently of said shaft and in circuit with said motor, the said auxiliary switches having reversely operating switch points actuated by throw-arms adapted to be alternately engaged by said traveling element, connection means between said throw-arms, and separate electrical conduits between the respective contact terminals of said auxiliary switches and their complementary contact terminals of said main switch.

In testimony whereof, I affix my signature.

HARVEY H. HALL.
